CLAIM

The ornamental design for a dispenser, as shown and described.

DESCRIPTION

FIG. 1 is a first perspective view of the dispenser
FIG. 2 is a second perspective view of the dispenser of FIG. 1.
FIG. 3 is a top plan view of the dispenser of FIG. 1.
FIG. 4 is a front plan view of the dispenser of FIG. 1.
FIG. 5 is a first side plan view of the dispenser of FIG. 1.
FIG. 6 is a back plan view of the dispenser of FIG. 1; and,
FIG. 7 is a second side plan view of the dispenser of FIG. 1.
Portions of FIGS. 1-7 are shown in dashed lines to depict
environmental subject matter only and form no part of the
claimed design.
